PLACE MAT OR THE LIKE

Richard M. Watts, Henrico County, Va., assignor to Reynolds Metals Company, Richmond, Va., a corporation of Delaware

Filed July 16, 1965, Ser. No. 86,186

Term of patent 14 years

(Cl. D92—26)

FIGURE 1 is a top plan view of the place mat or the like of this invention, the entire surface of the place mat being provided with a pebble embossment in the manner illustrated partially in full lines in FIGURE 1 whereby the pebble embossment is not only over the entire non-striped area of the mat, but also over the entire variegated striped area thereof;

I claim:

The ornamental design for a place mat or the like, as shown and described.
